CLAIM

We claim the ornamental design for a package, as substantially shown and described.

DESCRIPTION

FIG. 1 is an elevated perspective view of a package showing the sleeve;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is an elevated perspective view of the package showing the tray;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof;

FIG. 14 is a bottom plan view thereof;

FIG. 15 is an elevated view of the package showing the tray and the sleeve together; and,

FIG. 16 is an elevated exploded view thereof.

The broken lines in FIGS. 1-5 and FIGS. 8-12 depict portions of the package that form no part of the claimed design. The broken line showing of a bag (filled with circular items) in FIGS. 15 and 16 illustrates environmental subject matter and forms no part of the claimed design.
